US00D602,964S

(12) **United States Design Patent**
Hetcher et al.

(10) **Patent No.:** **US D602,964 S**
(45) **Date of Patent:** **** Oct. 27, 2009**

(54) **MITER SAW MOTOR HOUSING**

(75) Inventors: **Jason D. Hetcher**, Waukesha, WI (US); **Mark D. Willer**, Brookfield, WI (US); **Dennis J. Cerney**, Mukwonago, WI (US); **William A. Elger**, West Bend, WI (US); **Harold L. Papenfuss**, Menomonee Falls, WI (US); **Daryl S. Richards**, Sussex, WI (US); **David R. Bauer**, Delafield, WI (US); **Edward T. Gisske**, Mt. Horeb, WI (US); **Edward R. Raleigh**, Lodi, WI (US); **Michael E. Weber**, Hartland, WI (US); **Eric Fernandes**, Franklin, WI (US); **David Hlavac**, Germantown, WI (US); **Troy C. Thorson**, Waukesha, WI (US); **Michael L. Welliver**, Milwaukee, WI (US)

(73) Assignee: **Milwaukee Electric Tool Corporation**, Brookfield, WI (US)

(**) Term: **14 Years**

(21) Appl. No.: **29/240,624**

(22) Filed: **Oct. 14, 2005**

Related U.S. Application Data

(63) Continuation of application No. 29/227,851, filed on Apr. 15, 2005, now Pat. No. Des. 556,224.

CLAIM

The ornamental design for a miter saw motor housing, as shown and described.

DESCRIPTION

FIG. 1 is a front perspective view of a miter saw motor housing.

FIG. 2 is a front view of the motor housing of FIG. 1.

FIG. 3 is a rear view of the motor housing of FIG. 1.

FIG. 4 is a right-side view of the motor housing of FIG. 1.

FIG. 5 is a left-side view of the motor housing of FIG. 1.

FIG. 6 is a top view of the motor housing of FIG. 1; and,

FIG. 7 is a bottom view of the motor housing of FIG. 1.

The portions of the miter saw motor housing shown in broken lines in FIGS. 1-7 are included for the purpose of illustrating environment and form no part of the claimed design.

1 Claim, 7 Drawing Sheets
